COLLAR CAN COLLAR AND MOUNTING
THEREFOR

William F. Punte, Baltimore, Md., assignor to Continental Can Company, New York, N. Y., a corporation of New York

Application July 6, 1944, Serial No. 543,655

4 Claims. (Cl. 220—54)

1

The invention relates generally to metallic receptacles, and more particularly to the type known as collar cans wherein are provided tear strip structures adapted to be wound on keys and by this means torn out of the body walls of the cans in order to effect an opening thereof, and it primarily seeks to provide a novel collar structure for such cans and a novel mounting therefor.

In cans of the type stated the tear strips usually are defined by parallel score lines which surround the cans adjacent the upper end closure thereof, and a collar is snugly fitted within the upper end of each can in position for extending upwardly from the upper extremity of the can body resulting from the tearing out of the tear strip, thereby to maintain the desired can body wall height and provide a support neck over which the skirt or body wall portion remaining attached to the upper end closure can be telescoped to effect a reclosure of the can. It is the purpose of the present invention to provide a novel collar and mounting structure in which no raw metal edges are presented in position for being contacted by a hand of a user of the can, and in which the collar is held secure against movement downwardly or upwardly in the can.

Another object of the invention is to provide a novel collar and mounting therefor of the character stated in which the can body includes an inwardly directed bead just below the tear strip, and the collar includes a main body disposed within the can body opposite the tear strip and extending above and below the same, and an inwardly directed bead structure spaced within the can body bead and having upper portions resting as stop means on the can body bead and a lower outwardly and upwardly curled end extremity engaging the can body immediately below its bead, thereby to definitely place the collar with respect to the can body bead and avoid presentation of raw metal edge portions in position for being contacted by a hand of a user of the can.

Another object of the invention is to provide a collar of the character stated in which the upper portions of the bead structure resting as stop means on the can body bead constitute raw metal edge portions formed by slitting of the collar where it is bent inwardly to form its bead structure.

With the above and other objects in view that will hereinafter appear, the nature of the invention will be more clearly understood by reference to the following detailed description, the appended

2

claims, and the several views illustrated in the accompanying drawings.

In the drawings:

Figure 1 is a side elevation and part vertical cross sectional view of a can embodying the invention.

Figure 2 is an enlarged fragmentary vertical cross section taken on the line 2—2 on Figure 1.

Figure 3 is a view similar to Figure 2 illustrating the tear strip as torn out of the can body wall to effect an opening of the can and condition the closure as a reclosure element.

Figure 4 is a view similar to Figure 2 illustrating a slightly modified form of the invention in which the inwardly bent upper portion of the collar bead structure rests directly on the can body bead.

Figure 5 is an edge view of the strip from which the collar is formed.

Figure 6 is a face view of the strip shown in Figure 5.

Figure 7 is a fragmentary horizontal sectional view of the collar, the section being taken through the seam joining the ends of the collar.

Figure 8 is a vertical cross section of the collar prior to formation of the lower bead structure thereon.

Figure 9 is a view similar to Figure 8 illustrating the collar with the lower bead structure thereon formed prior to anchoring of the collar in the can body.

In this disclosure the invention is illustrated as embodied in a can including a can body 5 and the usual lower end closure 6 and upper end closure 7, both preferably seam secured to the body 5 in the manner well known in the art.

Near its upper end the body 5 is provided with an inwardly directed bead 8, and between the bead 8 and the upper closure 7 the body is scored in the conventional manner to provide a tear strip 9 adapted to be wound on a key and in this manner torn out of the can body wall to effect an opening of the can in the well known manner.

The improved collar includes a main body portion 10 which when mounted in the can snugly fits interiorly opposite the tear strip 9 and extending above and below said tear strip. The collar is provided at its upper extremity with an inwardly curled bead 11, and at its lower extremity with an inwardly directed bead structure including an inwardly bent upper portion 12, an upright wall 13 spaced inwardly from the can body bead 8, and an outwardly and upwardly bent portion 14 terminating in an edge which engages the can body 5 immediately below the bead 8.

It will be apparent by reference to Figures 1, 2, 6, 8 and 9 of the drawings that the collar is circumferentially slitted at space intervals as at 16, each said circumferential slit 16 merging at its ends with upwardly directed slitting 17 and the slitting 16 and 17 being provided at the point at which the collar wall is inwardly bent as at 12 in the formation of the collar bead structure. By thus slitting the collar wall structure 16, 17 and placing said slitting in the manner stated, inward bending of the collar wall as at 12 causes the wall portions defined by the slit equipments 16, 17 to remain vertical in the manner clearly illustrated in Figure 2 and provide raw edge stop shoulders 18 which rest upon the can bead 8 and anchor the collar against downward movement.

In the formation of the collar the initially formed bead structure 12, 13 has its lower edge extremity ducked in slightly as at 19 in the manner clearly illustrated in Figure 9. This permits the collar to be inserted over the can body bead 8, and the inwardly ducked portion 19 greatly facilitates outward and upward curling of the lower extremity of the collar as at 14 in the final securing of the collar in the can body. It will be apparent by reference to Figures 2 and 3 of the drawings that the collar bead structure embraces the can body bead 8 in spaced relation, with the raw metal stop shoulders or flanges 18 engaging the bead 8 from above, and the outwardly and upwardly curled lower edge extremity 14 engaging the can body as at 15 immediately below the can body bead 8. In this manner the collar is securely held against movement downwardly or upwardly in the can body, and no raw edge portions are presented in position for being contacted by a hand of a user of the can.

The collar may constitute a continuous drawn ring but in this disclosure it is shown as formed from a band or strip of metal having its ends joined by a seam in the manner clearly illustrated in Figures 7, 8 and 9. The band or strip from which the collar may be made is indicated at 20 in Figures 5 and 6, and this band is provided with a hook 21 at one end as illustrated at the left in Figures 5 and 6, and with a dove-tail offset 22 at its other end. By shaping the band 20 in the form of a circle and engaging the hook 21 in the dove-tail offset 22 and then closing the offset in the manner illustrated in Figure 7, an inwardly directed hook seam 23 may be formed.

It will be apparent by reference to Figures 5, 6, 8 and 9 that the seam formed by the hook and offset portions 21 and 22 terminates short of the ends of the collar as at 24, and thus the seam does not extend into the bead 11 at the top of the collar or the bead structure 12, 13 at the bottom of the collar. This makes it possible to abut the ends of the inwardly curled bead 11 as at 25 and also to abut the end of the collar bead structure 12, 13 as at 26 without providing any cumbersome overlaps. It will also be apparent by reference to Figure 9 that the inwardly directed curl 11 and the bead structure 12, 13 protect the upper and lower end extremity of the collar seam 23 against direct contact by a hand of a user of the can.

In Figure 4 of the drawings there is illustrated a slightly modified form of the invention in which the collar is not slitted in the manner illustrated in Figures 6 and 8 of the drawings. This modi-

fied form of collar includes a main body 27 and is inwardly curled as at 28 at its upper extremity. The inwardly bent portion 27 of the bead structure provided at the bottom of the collar provides a stop shoulder directly engageable with the can body bead 30, and said lower bead structure embraces the can body bead 30 in spaced relation and includes an upright wall portion 31 and an outwardly and upwardly turned lower edge extremity 32 which engages the can body wall immediately beneath the bead 30 as at 33. Thus in this form of the invention the collar is secured against upward movement by the upwardly and outwardly bent lower edge extremity 32 and the inwardly bent stop shoulder 29, the latter being disposed to directly rest upon the can body bead 30.

While one form of the invention has been shown for purposes of illustration, it is to be clearly understood that various changes in the details of construction and arrangement of parts may be made without departing from the spirit and scope of the invention as defined in the appended claims.

I claim:

1. In a sheet metal container, a body portion, an upper end closure seamed onto the body portion, said body portion having an inwardly directed bead adjacent its upper end and being scored above said bead to provide a tear strip, and a collar snugly fitting within the body and having a main body portion lying opposite and extending above and below the tear strip and terminating upwardly in an inwardly curled bead and downwardly in an inwardly directed bead structure including an upright wall portion spaced inwardly from the can body bead, shoulder means engaging the upper portion of the can body bead and preventing downward movement of the collar and an outwardly and upwardly curled lower end extremity engaging the can body wall immediately below the can body bead.

2. Container structure as defined in claim 1 in which the can body bead engaging shoulder means constitutes downwardly directed raw metal flanges formed by slitting the body portion of the collar at the juncture with the lower inwardly directed bead structure thereof.

3. A collar for collar cans comprising a cylindrical body having at its lower end a bead structure adapted to fit within a can body bead and including an inwardly and downwardly bent portion extending from said body, said body being provided with a plurality of circumferential slits at the juncture of said bent portion with said body disposed to provide raw metal stop flanges adapted to rest upon a can body bead.

4. A collar for collar cans comprising a cylindrical body having at its lower end a bead structure adapted to fit within a can body bead and including an inwardly and downwardly bent portion extending from said body, said body being provided with a plurality of circumferential slits at the juncture of said bent portion with said body disposed to provide raw metal stop flanges adapted to rest upon a can body bead, said body terminating upwardly in an inwardly curled bead and having an inwardly directed body end connecting hook seam disposed between and protected against hand contact by the inwardly curled bead and the inwardly and downwardly bent portion.

WILLIAM F. PUNTE.
